CLAIM

The ornamental design for a crayon mini, as shown and described.

DESCRIPTION

FIG. 1 is a front elevation view of a crayon mini, the rear elevation view being a mirror image of the front;

FIG. 2 is a top plan view thereof;

FIG. 3 is a bottom plan view thereof;

FIG. 4 is a side elevation view thereof, rotated 90 degrees in two directions from the view shown in FIG. 1; and,

FIG. 5 is a perspective view thereof.
